US0D1016833S

(12) **United States Design Patent** (10) Patent No.: **US D1,016,833 S**
Ceniceroz (45) Date of Patent: ** Mar. 5, 2024

(54) **DISPLAY SCREEN OR PORTION THEREOF WITH A GRAPHICAL USER INTERFACE**

(71) Applicant: **IGT**, Las Vegas, NV (US)

(72) Inventor: **David Ceniceroz**, Reno, NV (US)

(73) Assignee: **IGT**, Las Vegas, NV (US)

(**) Term: **15 Years**

(21) Appl. No.: **29/876,419**

(22) Filed: **May 22, 2023**

Related U.S. Application Data

(60) Continuation of application No. 29/866,424, filed on Sep. 12, 2022, now Pat. No. Des. 992,579, which is a division of application No. 29/743,414, filed on Jul. 21, 2020, now Pat. No. Des. 966,330.

(57) **CLAIM**

The ornamental design for a display screen or portion thereof with a graphical user interface, as shown and described.

DESCRIPTION

FIG. 1 is a front view of a display screen or portion thereof with a graphical user interface showing a first embodiment of my new design; and,

FIG. 2 is a second embodiment thereof.

The dot dashed broken line showing the display screen or portion thereof forms no part of the claimed design. The dashed broken line showing portions of the graphical user interface forms no part of the claimed design.

1 Claim, 2 Drawing Sheets
